CLAIM

The ornamental design of a retractable tape measure for left hand gripping, substantially as shown and described.

DESCRIPTION

FIG. 1 is a perspective view of the subject retractable tape measure, shown with the tape partly withdrawn from the case;

FIG. 2 is a top view of the subject retractable tape measure; FIG. 3 is a rear elevational view of the subject retractable tape measure;

FIG. 4 is a front elevational view of the subject retractable tape measure;

FIG. 5 is a right side elevational view of the subject retractable tape measure;

FIG. 6 is a left side elevational view of the subject retractable tape measure;

FIG. 7 is a bottom view of the subject retractable tape measure with the tape partly withdrawn from the case; and, FIG. 8 is a bottom view of the subject retractable tape measure with the tape fully retracted within the case.
